Primary Examiner—Stella Reid**Attorney, Agent, or Firm**—Herzog, Crebs & McGhee, LLP**[57] CLAIM**

The ornamental design for a nursing bottle with indented sides, as shown and described.

DESCRIPTION

FIG. 1 is a right top front perspective view of a nursing bottle with indented sides, showing our new design;

FIG. 2 is a front elevational view thereof;

FIG. 3 is a left side elevational view thereof, the right side elevational view being identical;

FIG. 4 is a top plan view thereof;

FIG. 5 is a bottom plan view thereof; and,

FIG. 6 is a cross-sectional view taken along line 6—6 of FIG. 2.
